DESIGN FOR AN INCANDESCENT LAMP

Matthew Luckiesh, Shaker Heights, Ohio

Application July 29, 1943, Serial No. 110,789

Term of patent 7 years

To all whom it may concern:

Be it known that I, Matthew Luckiesh, a citizen of the United States, residing at Shaker Heights, in the county of Cuyahoga and State of Ohio, have invented a new, original, and ornamental Design for an Incandescent Lamp, of which the following is a specification, reference being had to the accompanying drawing, forming a part thereof, in which

Fig. 1 is an elevational view of an incandescent lamp embodying my new design; and

Fig. 2 is a bottom view of the same.

The bowl or hemispherical portion of the bulb of the lamp is stippled to indicate diffusing material.

I claim:

The ornamental design for an incandescent lamp, substantially as shown and described.

MATTHEW LUCKIESH.
